[57] CLAIM

The ornamental design for a telephone base, as shown and described.

DESCRIPTION

FIG. 1 is a top view of the telephone base, showing our new ornamental design;

FIG. 2 is a further top view thereof with section lines; FIG. 3 is a fragmentary sectional view taken along line 3—3 of FIG. 2, for showing only the outer contours taken at the section line through the cradle region of the base;

FIG. 4 is a fragmentary sectional view taken along line 4—4 of FIG. 2, for showing only the outer contours taken at the section line through the right side of the base;

FIG. 5 is a right side elevation of the base;

FIG. 6 is a front elevation thereof;

FIG. 7 is a left side elevation thereof;

FIG. 8 is a rear elevation thereof; and,

FIG. 9 is a further right side elevation of the base, showing a handset in the cradle portion of the base.

All items shown in broken lines are shown for illustrative purposes only and form no part of the claimed design.
